UNITED STATES PATENT OFFICE

ZENAS P. CANDEE, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT

GAUGING MECHANISM

Application filed April 6, 1928. Serial No. 267,989.

My invention relates to new and useful improvements in gauging mechanisms and particularly to mechanism for gauging or inspecting articles, particularly shells for cartridges or the like, but is not limited, however, to such use.

It is the object of this invention, among other things, to provide mechanism for automatically gauging or inspecting an article with extreme accuracy, and to automatically eject such of the articles as have failed to meet the gauging test, preferably so that they are segregated into groups, one for each gauging test.

15 This improved gauging mechanism may be used for the same general purpose as the mechanism disclosed in Letters Patents of the United States, No. 1,602,334, issued October 6, 1926, for improvements in loading machines, and No. 1,652,298, issued December 13, 1927, for improvements in gauging machines.

In the drawings, wherein like numerals of reference designate like parts in the several figures;

Figure 1 is a fragmentary plan view of a machine having my improved gauging mechanism forming part thereof;

Figure 2 is an enlarged sectional view 30 thereof, taken generally upon line 2—2 of Figure 1;

Figure 3 is an enlarged sectional view thereof, taken generally upon lines 3—3 of Figure 1;

35 Figure 4 is a front view of a portion of the mechanism illustrated in the preceding figure; and

Figure 5 is an enlarged cross sectional view 40 of a portion of the discharge mechanism, taken generally upon line 5—5 of Figure 1.

In the operation of this machine the articles are guided from a dial or other mechanism and conducted by any convenient mechanism to a plurality of stations where the 45 article is automatically gauged. If these successive gaugings are within the allowable tolerances, the articles are discharged from the machine into a conveniently arranged receptacle.

50 The machine is so designed and constructed

that there is no tendency for any of the parts to spring and thus tend to inaccuracy of the gauging. If any article fails to meet any gauging test within the allowable tolerances, means are set in motion by the gauging mechanism that discharges such article after the gauging test is completed. All articles that have failed to meet the gauging test at any one station are discharged at the same point. Hence the articles are assembled in different places determined by their defective character as disclosed by such tests and are not assembled in a single group as has been the general practice heretofore, and determination of the defects therein ascertained by manual means.

55 In the form which I have chosen to illustrate my invention, 10 indicates the bed plate that is supported upon standards 11 and 12 that may in turn be supported upon a base member 13. Fixed on this bed is a table 14 and associated therewith is a guide bar 15 and one or more bars 16 and 17, upon which the cartridges roll to and between the several inspection stations.

60 Fixed to the table 14 are a plurality of journal blocks 18 and hinged to each block is a rock arm 19 carrying a holder 20 that is movable in a substantially vertical plane toward and away from the article to be gauged, illustrated herein as a cartridge, this movement being derived through a rock arm 21 actuated by means not shown. The articles are moved over the guide plate 22 and are carried to the several gauging stations

65 by carrier bars 23, which constitute no part of my present invention. These bars are so arranged and operated that when the holder 20 moves upwardly and away from the article the bars move downwardly and engage the articles, one article in each of several notches in their lower edges, then move substantially parallel with the top of the table 14 and the articles are moved to the next station.

70 When in register therewith, the holder moves downwardly and engages and holds the articles in position for the gauging operation and the carrier bars move to their former position for the next feed movement.

75 Movable in the frame 24 upon opposite

sides of the machine are the slides 25 and 26, the former deriving its movement through links 31 from the cam 29 upon shaft 30 through rock arms 27 and 92 upon the shaft 28.

Stop screws 32 in lugs 33 abut against the fixed lugs 34 and by means of which the limit of movement of the slide 25 in one direction may be varied. A spring 35 exerts its tension so as to maintain the cam roll 36 on the rock arm 27 in contact with the cam 29.

The slide 26 is actuated from a cam 37 on the shaft 30 through a rock arm 38 fixed on a rock shaft 39 supported in journal blocks 44, and carrying a rock arm 40, which is connected with the slide through the link 41; a spring 42 exerting its tension so as to maintain the roll 43 in contact with the cam 37.

Fixed on the slide 26 are a plurality of blocks 45, in each of which is a slide 46, having a pin 47 that engages the wall of a slot 48 in the block 45 to limit the movement of the slide in one direction. Secured to the head of the slide 46 by a nut 49 is a gauging plate 50 having an opening 51 therethrough.

On the slide 26 near each of the blocks 45 is a bracket 52, in which is journaled a trip lever 53, the upper end of which is held against the slide 46 by the spring 56 and the lower end is movable into and out of the path of the trip balls 54, which travel in the groove of the worm 55. This worm and the trip balls associated therewith are substantially the same as disclosed in the said Patent No. 1,602,334.

Fixed to the worm housing 57 are a plurality of journal blocks 58, equal in number to the slides 46, in each of which is hinged a rock arm 59 having a cam face 60 thereon that projects over the worm 55 to a point adjacent to a line drawn vertically with the center thereof.

In the drawings I have illustrated two forms of gauging levers, one of said forms being shown in section in Figure 2 and the other in Figure 3.

Referring now more particularly to the form shown in Figure 2, 61 indicates a head member, into which is threaded a sleeve 62, which is held in any of its adjusted positions by the nut 63. Slidable through this sleeve is a gauging rod 64 having a hardened button 65 at its outer end. Journaled in the blocks 66 held in the head member 61 is the gauging lever 67 carrying a hardened plug 68 at its outer end. Secured to this gauging lever is a gauging plate 69, the outer end of which is maintained in contact with the rod 64 by a spring 70 supported on the post 71. An adjusting screw 72 provides means for varying the position of the gauging plate, which is locked in its several positions by the screws 73 or the like. The forward end of the gauging rod 64 is guided and aligned 65 with the article in its gauging position by

the fixed plate 74. The gauging lever 67 is so formed that the space between the center of the fulcrum thereof that is the axis of the journals in blocks 66 and the outer end of the plug 68 is ten times the distance between said center and the axis of the gauging rod 64, so that any movement of the gauging lever by reason of the variation in position of the rod 64 parallel to its axis is increased ten times at the plug 68. Any variation, therefore, in the position of the end of the button 65 by reason of its contact with the article is magnified ten times in the movement of the plug 68. If the article is too short, then the plug 68 is moved upwardly, if too long, then in the opposite direction, these two extremes being substantially shown by the broken lines in Figure 2. The proportion of ten to one as just described is arbitrary and may be varied as desired.

The opening 51 in the gauging plate is of such size that it will permit the plug 68 to enter therein within the extremes of the tolerances of variation in the length of the article. To illustrate; if the allowable tolerance in the length of the article is plus or minus .002" there will be an overall tolerance of .004". As the position of the plug 68 is out of alignment ten times that of the length of the article, the opening 51 would be .04" larger than the diameter of the plug 68, so that within the extremes of tolerance the plug 68 would still enter said opening 51 but if the length of the article is outside of such limits then the plug 68 would be moved to such position that it would be outside of the opening 51 and would engage the face of the plate 50.

In operation the articles, shown herein as cartridges, are moved to the respective gauging stations and there held by the holder 20, the slide 25 then moves forward carrying with it the gauging rod 64, which contacts with the cartridge. If the latter is correct in length no movement is imparted to the gauging lever 67. If, however, it is either above or below such length, but within the allowable tolerances, the plug 68 will be moved to a position wherein it will still be in alignment with the opening 51 in the gauging plate 50.

When the gauging rod 64 is in contact with the cartridge, all of the moving parts of the machine come to a rest position, thus eliminating all possibility of vibration of any of the parts. When the parts have thus come to a rest the slide 26 moves forward and if the cartridge is either the correct length or within its tolerance limitations, the plug 68 will enter the hole 51 in the gauging plate 50 without imparting movement thereto. If, however, the cartridge is not of the proper length and outside its allowable tolerances, the gauging plate 50 will engage the end of the plug 68 and the slide 46 will move within the block 45 during the further movement of the slide 26. This action will cause the trip le-

120

125

130

ver 53 to rock upon its pivot mounting, engage the trip ball 54, and move the same in the groove of the worm 55 so that it is on the opposite side of the center thereof. In this new position, outlined by broken lines in Figure 2, the ball 54 will actuate the rock arm 59 during the rotation of the worm and through which the discharge mechanism is actuated as hereinafter described. In brief, if the cartridge is correct in length, or within the limits of the allowable tolerances, the plug 68 enters the opening 51 in the gauging plate and the discharge mechanism is not actuated. If, however, its length is not within such limits 10 the plug does not enter said opening and the discharge mechanism is actuated as a result thereof.

Substitution of a new gauging rod 64 or variation of the position of the sleeve 62, or 20 both, permits the use of this mechanism for cartridges that vary considerably in their overall length without substitution of other parts.

Adjacent to each of the inspecting stations 25 is a chute 75 through the table 14, the lower edge of which is opposite a discharge chute 76 that is supported in part by a bracket 80. One wall of the chute 75 is closed by the hinged gate 77 between which and the rock 30 arm 59 is a push rod 78. When the gate 77 is in the position shown in Figure 2, the cartridge rides thereover during its travel from one station to another, but if the preceding cartridge has not measured up to the gauging 35 test, the ball 54 actuates the rock arm 59 in the manner heretofore described and this in turn moves the gate 77 upon its mounting through the rod 78 against the tension of the spring 79, so that it occupies the position shown in 40 Figure 5. The support for the cartridge now being removed it drops through the chute 75 into the discharge chute 76. Thus, all cartridges rejected for a single defect are discharged at one station and are grouped together in a convenient receptacle.

In Figure 3 is illustrated the form of gauging mechanism for the diameter and width of the groove, the diameter of the head, etc. In this form the lever 81 is also provided with 50 a plug 68 that in one of its positions registers with the opening 51 in the gauging plate 50, in the manner above described. The lever is hinged at 82 to a bracket 83 connected with the table 14 and carries at its inner end a gauging plate 84. Upon the lower end of this lever is a cam lug 85 which contacts with a roll 86 upon a plate 87 adjustably connected with the bracket 25.

Fixed in the bracket 88 adjustably connected with the bracket 83 is a blade 89 and a backing plate 90. With this form of lever, as the cartridge is moved into the gauging position the rear face thereof abuts against the backing plate 90 and the lower edge of the 65 blade 89 enters the groove at the head of the

cartridge. The slide 25 now moves toward the table 14 and the position of the lever 81 about its pivot is determined by the relative position of the blade 89, and the contact of the lug 85 with the roll 86. Thus, the plug 70 68 is in or out of register with the opening 51 in the gauging plate 50 as the cartridge may pass or fail in the gauging test. The spring 91 exerts its tension so as to maintain the lug 85 and roll 86 in contact with each other. It is desirable that the blade 89 should be positioned high enough to allow a cartridge with no groove in its shell to pass thereunder. The arrangement of these 75 blades may be such as to determine the width and depth of the groove, the thickness of the head of the cartridge, the diameter thereof, etc. The operation of the slide 26 and the discharge mechanism is the same with this 80 form of gauging lever as the one first above described.

In effect the levers 67 and 81 and associated 85 parts constitute an inspector or gauging element and in operation this inspector is in turn inspected by the slide 46 and its associated parts.

By the use of a gauging member as herein shown and described, the cartridge may be gauged in various ways with extreme accuracy, great speed, and by mechanism that is 90 comparatively simple in its operation, and the cartridges that do not meet the gauging tests are discharged and grouped according to their several defects.

Tools, blades, and other devices may be 95 substituted for the button 65 and blades 84 and 89 to provide for other gaugings than can be made therewith, and are within my invention.

There are other minor changes and alterations that may be made within my invention, aside from those herein suggested, and I would therefore have it understood that I do not limit myself to the exact construction 100 herein shown and described, but claim all that falls fairly within the spirit and scope 105 of the appended claims.

Having described my invention, what I 110 claim as new and desire to secure by Letters Patent, is:

1. Means for gauging an article, comprising an inspector mechanism, the position of which is determined by the article; and a second inspector mechanism having a substantially right line movement toward and away from the first inspector mechanism, the extent of such movement being determined by the position of the first mentioned inspector mechanism if the latter is not in a predetermined position or allowable variations therefrom.

2. Means for gauging an article, comprising an inspector mechanism, the position of which is determined by the article; means for moving such mechanism as a unit; a second 120

inspector mechanism; means for independently moving the second inspector mechanism as a unit after the first mentioned inspector mechanism has come to a rest position, the 5 movement of a portion of the second inspector mechanism being interrupted by the first mentioned inspector mechanism if the latter is not in a predetermined position or allowable variations therefrom.

10 3. Mechanism for gauging an article having a lever, one part of which is adjacent to and its position determined by the article; and a member movable in a substantially straight line toward and away from the lever, 15 the extent of such movement being limited by the lever, if that part thereof adjacent to the article is not in a predetermined position.

4. Mechanism for gauging an article having a lever, one part of which is adjacent to 20 and its position determined by the article; a member movable in a substantially straight line toward and away from the lever, the extent of such movement being limited by the lever, if that part thereof adjacent to the 25 article is not in a predetermined position; and means set in motion by said member for segregating the article when the extent of movement of said member is limited by the lever.

30 5. Mechanism for gauging an article having a lever, one part of which is adjacent to and its position determined by the article; a member movable relatively to the lever which registers with and in part passes over the 35 lever if that part of the lever adjacent to the article is in its predetermined position.

6. Mechanism for gauging an article having a lever, one part of which is adjacent to and its position determined by the article; a 40 member having an opening therein that is movable relatively to the lever, said opening receiving a portion of the lever if that part of the lever adjacent to the article is in a predetermined position.

45 7. Mechanism for gauging an article having a lever, one part of which is adjacent to and its position determined by the article; an element movable relatively to the lever; a member movable within the element and 50 actuated therein by the lever if that part thereof adjacent to the article is not in a predetermined position.

8. Mechanism for gauging an article, comprising in part two elements movable relatively to each other; a lever connected with 55 one of the elements and in one of its positions one part of the lever being adjacent to and in a position determined by the article; a member movably mounted in the other element and actuated by the lever if that part of the lever adjacent to the article is not in a predetermined position; and means for actuating 60 said elements whereby the one having a lever connected therewith comes to a full stop before the other element begins its movement.

9. Mechanism for gauging an article having a lever, one part of which is adjacent to and its position determined by the article; a support for the article; a member movable relatively to the lever and actuated thereby 70 if that part of the lever adjacent to the article is not in a predetermined position; and means set in motion by said member for moving a portion of the support of the article when actuated by the lever, whereby the article will move out of its former path and be segregated from those articles that permit the lever to move into a predetermined position. 75

10. Mechanism for gauging an article having a lever, one part of which is adjacent to 80 and its position determined by the article; a support for the article; a member movable relatively to the lever and actuated thereby if that part of the lever adjacent to the article is not in a predetermined position; means 85 set in motion by said member for moving a portion of the support of the article when actuated by the lever, whereby the article will move out of its former path and be segregated from those articles that permit the 90 lever to move into a predetermined position, comprising in part a trip member; and intermediate mechanism between a rock member and support having a transitory element which is moved from an inoperative to an 95 operative position and thereby actuates the movable portion of the support if the lever is not moved into its predetermined position.

11. Mechanism for gauging an article having a lever, one part of which is adjacent to 100 and its position determined by the article; a member having an opening therein that is movable relatively to the lever and registers with a portion of the lever if that part of the lever adjacent to the article is in its predetermined position, said opening being of substantially the same diameter as the part of the lever that registers therewith plus the allowable tolerance of variation in the article being gauged. 105

12. Mechanism for gauging an article comprising in part two slides; means for independently actuating each of the slides; a lever connected with one of the slides and in one of its positions one part of the lever being adjacent to and in a position determined by the article, another slide associated with and movable relatively to the second of said slides and having an opening therein to receive a part of the lever within the allowable tolerances of variation in the article that is actuated by the lever if said article is outside of said allowable tolerances, and means for actuating said slides whereby the one having a lever associated therewith comes to a rest position before movement is imparted to the said second slide. 115 120 125

13. Mechanism for gauging an article, comprising in part two slides; means for independently actuating each of the slides; a 130

lever connected with one of the slides and in one of its positions one part of the lever being adjacent to and in a position determined by the article, another slide associated with and movable relatively to the second of said slides and having an opening therein to receive a part of the lever within the allowable tolerances of variation in the article that is actuated by the lever if said article is outside of said allowable tolerances, means for actuating said slides whereby the one having a lever associated therewith comes to a rest position before movement is imparted to the said second slide, a transitory element, a trip member carried by the second slide and actuated by the slide mounted therein when in one of its positions, and a movable support for the article that is actuated through the transitory member.

14. Mechanism for gauging an article, comprising in part two slides; means for independently actuating each of the slides, a lever connected with one of the slides and in one of its positions one part of the lever being adjacent to and in a position determined by the article, another slide associated with and movable relatively to the second of said slides and having an opening therein to receive a part of the lever within the allowable tolerances of variation in the article, means for segregating the article that does not meet the gauging tests, said means being set in motion by the slide associated with the second slide when engaged by the lever during movement of the second slide, if the lever is not in a predetermined position.

15. Mechanism for gauging an article having a lever, one part of which is adjacent to and its position determined by the article; a member movable relatively to the lever and actuated thereby if that part of the lever adjacent to the article is not in a predetermined position, and spring means that exerts its tension so as to normally hold said lever in one of its positions.

16. Means for gauging an article, comprising an inspector mechanism, the position of which is determined by the article; means for moving such mechanism as a unit; a second inspector mechanism; means for moving the second inspector mechanism as a unit after the first mentioned inspector mechanism has come to a rest position, the movement of a portion of the second inspector mechanism being interrupted by the first mentioned inspector mechanism if the latter is not in a predetermined position or allowable variations therefrom; and means set in motion by said second inspector mechanism for segregating the article when said second inspector mechanism is actuated by the first mentioned inspector mechanism.

17. Mechanism for gauging an article having a lever, one part of which is adjacent to and its position determined by the article;

a member movable relatively to the lever which registers with and in part passes over the lever if that part of the lever adjacent to the article is in its predetermined position and completes its movement without being actuated by the lever.

In testimony whereof, I have hereunto affixed my signature.

ZENAS P. CANDEE.
